UNITED STATES PATENT OFFICE

2,466,638

BRASSIÈRE

Harriette A. Denis, Los Angeles, Calif., assignor of
one-half to Earl Schmaltz, Long Beach, Calif.

Application March 13, 1947, Serial No. 734,393

3 Claims. (Cl. 2—42)

1

This invention relates to brassières and has for an object to provide a women's garment of this character which is separable at the front rather than at the rear as in conventional brassières, to facilitate donning thereof.

Another object of the invention is to provide a brassière which is formed of back-connected similar breast-supporting pockets separably joined at the front for greater convenience in donning thereof.

Another object of the invention is to provide an improved brassière structure in which each pocket is formed of a single piece of woven material having the warp and weft threads so directed that the said material resists stretch in the direction around the body and is on a bias for suitable stretch in the breast engaging portions.

My invention also has for its objects to provide such means that are positive in operation, convenient in use, easily installed in a working position and easily disconnected therefrom; economical of manufacture, relatively simple; and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a perspective view of a brassière according to the invention and shown in use.

Fig. 2 is a broken view of one pocket-forming brassière part in flat or pattern condition drawn to an enlarged scale.

The present brassière comprises identical but oppositely formed breast-supporting pockets 5 which are connected together at the back by rigid or elastic means, a separable fastener 6 connecting said pockets at the front, and, optionally, straps 7 for supporting the brassière from the shoulders.

Each pocket 5 is formed of a single piece of woven material as shown in Fig. 2. Said piece of material is formed with an upper laterally directed part 8, a lower oppositely laterally directed part 9 and a transverse intermediate connecting part 10 whereby said piece of material is generally Z-shaped with the part 9 considerably longer than the part 8.

The part 8 is defined by an end edge 11, a bot-

2

tom reversely curved edge 12, and an upper edge which comprises edge portions 13 and 14, which include an obtuse angle.

The part 9 is defined by a slightly concavely curved bottom edge 15 and similar oppositely curved upper edge 16 which curves more sharply outward as it approaches the end of edge portion 14.

The transverse part 10 is defined by a reversely curved edge 17 substantially at right angles to the edge 12; an adjacent extension of the edge 15, and the adjacent portions of the edges 14 and 16.

As shown, either the warp threads or the weft threads of the material extend laterally, i. e., longitudinally of the parts 8 and 9 so that said parts, in themselves, have no longitudinal stretch.

The piece of material above described is formed into a breast-supporting pocket 5 by bringing the edges 12 and 17 together and sewing along the line 18 shown in Fig. 1. A bulge in the material is thus created to receive the breast. It will be noted that the warp threads which are horizontal in the part 8 are now generally vertical and that the initially vertical weft threads of said part align themselves with the horizontal warp threads of part 9 so that longitudinal stretch of the pocket is obviated.

It will be further noted that, with respect to point 19 which resides on the vertical center line of the pocket, the warp and weft threads are on a bias so that the bulge thus formed has both vertical and horizontal stretch whereby said pocket seeks a domed breast-contouring shape. The dash line 20 of Fig. 2 indicates said vertical center line and reveals the bias disposition of the material.

The curved dot-dash lines 21, on opposite sides of the line 20, represent the location of a tape which is sewn to the under face of each pocket to define the stretchable bulge apart from non-stretchable parts of the pocket. A similar tape may be applied along the lower edge of each pocket 5.

The fastener 6 is shown as a separable slide fastener of conventional form and its cooperating parts are sewn to the edge part 13 of each pocket. Said edge part, being substantially on the "straight" of the material, the longitudinal pull of the pockets is taken directly by said fastener without undesired stretch.

The straps 7 are generally of typical form and complete the brassière so that the same can be donned in a manner similar to coat or vest and the fastener 6 connected.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a brassière of the character described, similar breast-supporting pockets separably connected at the front, each pocket being formed of a single piece of woven material having an upper laterally directed portion, a lower oppositely directed portion and a generally transverse connecting portion, the warp threads of the material being directed along the length of the laterally directed portions, said upper lateral portion having a reversely curved lower edge and said transverse portion having a similar edge forming an angle with said lower edge, and said edges being adapted to be joined to form a breast-receiving bulge in which said warp threads have a bias direction, tapes secured to the underside of each pocket to define the stretchable area from the non-stretchable area said upper lateral portion having an upper edge formed by edge portions which include an obtuse angle, the end edge of said upper lateral portion comprising a part of the bottom edge of the pocket.

2. In a brassière of the character described, similar breast-supporting pockets separably connected at the front, each pocket being formed of a single piece of woven material having an upper laterally directed portion, a lower oppositely directed portion and a generally transverse connecting portion, the warp threads of the material being directed along the length of the laterally directed portions, said upper lateral portion having a reversely curved lower edge and said transverse portion having a similar edge forming an

angle with said lower edge, and said edges being adapted to be joined to form a breast-receiving bulge in which said warp threads have a bias direction, the bulge having means to limit the stretchable area said upper lateral portion having an upper edge formed by edge portions which include an obtuse angle, the end edge of said upper lateral portion comprising a part of the bottom edge of the pocket and the adjacent mentioned edge portion comprising the outer end edge of said pocket.

3. In a brassière of the character described, similar breast-supporting pockets separately connected at the front, each pocket being formed of a single piece of woven material having an upper laterally directed portion, a lower oppositely directed portion and a generally transverse connecting portion, the warp threads of the material being directed along the length of the laterally directed portions, said upper lateral portion having a reversely curved lower edge and said transverse portion having a similar edge forming an angle with said lower edge, and said edges being adapted to be joined to form a breast-receiving bulge in which said warp threads have a bias direction and whereby said end edge of the upper lateral portion and the bottom edge of the lower oppositely directed portion form a continuous lower edge of the pocket.
